DATA RECORDING PROJECTION MACHINE

Frank E. Anderson, Brooklyn, N. Y., assignor, by
mesne assignments, to James W. DeckerApplication May 9, 1931, Serial No. 536,312
Renewed May 29, 1935

12 Claims. (Cl. 271—2.3)

This invention relates to data recording projection machines in general and more especially to stock quotation projection machines in which the actuating motor for the tape pulling device is operated continuously.

Among the objects of the present invention, it is aimed to provide an improved device for pulling the tape through a stock quotation projection machine whereby the motor is continuously operated and a tape pulling device positively controlled to vary its speed according to the speed of discharge of the tape by the ticker.

It is still another object of the present invention to provide an improved variable friction drive for the tape pulling device of a stock quotation projection machine whereby the speed of the tape pulling device is changed to correspond to the speed of discharge of the tape from the ticker and simultaneously therewith.

It is still another object of the present invention to provide an improved tape pulling device for a stock quotation projection machine in which the speed is positively varied to correspond simultaneously with the speed of discharge of the tape which can be constructed at a minimum cost and can be operated without the attention of a skilled mechanic.

It is still another object of the present invention to provide an improved tape mounting reel.

These and other features, capabilities and advantages of the invention will appear from the subjoined detail description of one specific embodiment thereof illustrated in the accompanying drawings in which

Figure 1 is a side elevation of a stock quotation projection machine made according to the present invention with the projection screen omitted;

Fig. 2 is a plan view of the same;

Fig. 3 is a fragmental longitudinal section showing part of the controlling means in detail;

Fig. 4 is a section on the line 4—4 of Fig. 3;

Fig. 5 is a fragmental section of a view of the improved reel with the removable disc shown in dash and dot lines;

Fig. 6 is a fragmental end elevation of the removable disc portion of the wheel; and

Fig. 7 is a fragmental detail showing the anchoring means for the removable disc portions of the reel.

In the embodiment illustrated, there is provided a ticker 1 of the high speed type today in use from which the tape T passes under the finger 2 and thereupon passes over the light aperture 3 formed in the end of the lamp house extension 4 extending from the side of the lamp house

5. From the light aperture or projection field 3, the tape passes down under the tape pulling roller 6 and then over onto the reel 7.

The light aperture 3 preferably has provided at its entrance end a guide piece 8 consisting of two upwardly extending projections between which the tape T passes to the light aperture. At the discharge end of the light aperture, there is provided a similar guide piece 9 consisting of similar upwardly extending projections through which the tape T passes as it leaves the light aperture on its way to the tape pulling roller 6.

Above the light aperture 3, there is provided the objective lens 10 which is preferably secured in the casing 11 formed at the end of the bracket 15 12 extending upwardly from the lamp house extension 4.

The light rays in the usual way pass upwardly from the extension 4 through the light aperture 3 onto the tape T and after receiving the image 20 pass on to the objective lens 10 to a suitable screen casing or housing not shown.

The present invention is mainly concerned with the tape pulling device according to which the element which controls the movement of the 25 tape also irons out the vibrations transmitted to the tape by the ticker in accordance with the principle set forth in the Proctor Patent No. 1,299,024.

The finger 2 is in the nature of a roller in the 30 present instance having a raised edge 13 in the middle thereof to engage the tape between the two rows of type which are ordinarily formed on the average ticker tape. This roller 2 is rotatably mounted on a shaft formed on the end of the 35 short arm portion 14, formed at the end of the elongated arm portion 15 which is secured at 16 to the pin 17 fixed onto the arm 18 extending in line with the arm portion 15 inside of the 40 housing 19.

The end of the arm 18, see Fig. 3 is provided with a bifurcation 20 having slots 21 in its bifurcated ends to receive the pins 22 extending outwardly from the enlarged portion 23 of the spindle 24 slidably mounted in the worm 25 fixed to rotate therewith having a keyway 26 formed therein to receive a key formed on the worm 25. The worm 25 is fixed to rotate between the bearings 27 and 28 secured to the rear wall 29 of the 50 housing 19.

The upper end of the spindle 24 is rotatably mounted in the bearing 30 also secured to the end wall 29. The upper wall portion 31 of the housing 19 is provided with a chambered exten- 55

sion 32 to permit the end of the spindle 24 slidably to extend into the same.

Between the bearing 30 and the bearing 27, there is formed a friction wheel 33 which is secured in place by any suitable means and consists essentially of some compressible substance, such for instance as rubber. This wheel has a large bearing surface as shown in Fig. 3 which engages the friction disc 34 spaced from the center of the disc from a point above the same according to the speed to be attained. The disc 34 is slidably secured to the disc portion 35 by the pin 36 but urged outwardly by the spring 37 formed in the center recess 38 of the shaft portion 39, the spring 37 pressing the friction disc 34 into frictional contact with the frictional wheel 33.

The shaft 39 is mounted in the journal 40 secured to the wall 41 which is provided with the bearings 42 disposed between the collar 43 and the shoulder portion 44 on the shaft 39, the collar 43 being threadly connected to the end of the journal 40 in order to adjust the portion of the shaft and therewith the disc 34 relative to the friction wheel 33.

On the end of the shaft 39, there is formed the pulley 45 having a hub 46 which is secured to the shaft 39, in any suitable manner, the screws 47 being illustrated in the present instance. The pulley 45 is connected by the spring belt 48 in the present instance to the sheave 49 formed on the shaft 50 of the motor 51, see Fig. 1.

The worm 25 meshes with the worm wheel 52, see Fig. 3, mounted on the shaft 53 extending through the housing 19 and having on one end the tape pulling roller 6, see Figs. 1 and 2 and on the other end the sheave 54 which is connected by the spring belt 55 with the sheave 56 on the shaft 57 mounted in the bracket 58. The shaft 57, see Fig. 5, has formed thereon the reel 7.

The arm 18 is tensed upwardly by the spring 59 extending from the arm 18 to the abutment 60 formed on the front wall 61 of the housing 19. From the foregoing, it will be seen that as the ticker operates to form the loop L between the ticker and the projection field 3, the finger 2 engaging the same will permit the arm portions 14 and 15 to descend thereby causing the arm 18 to rise and move the spindle 24 upwardly through the worm 25 and bearing 30 to cause the friction wheel 33 to rise above the center of the friction disc 34. The friction disc 34 being constantly rotated through its connection with the motor 51 will obviously transmit a greater speed to the friction wheel 33 as the friction wheel 33 approaches the periphery of the friction disc 34.

In turn as the ticker stops and the tape pulling motor continues to operate the slack L will of course be taken up in turn to cause the arm portions 14 and 15 again to ascend and thereby cause the arm portion 18 to descend to return the friction wheel 33 to the center of rotation of the disc 34, at which portion of the disc 34, the friction wheel 33 is maintained at rest.

It will be noted that the spring 59 merely operates with the levers 14 and 15 and arm portion 18 so that the slack formed by the ticker in the tape T will be followed up as quickly as possible and thus prevent any snapping or sudden drop of the lever portions 14 and 15 when the ticker starts operating to strike the tape and cause the same to vibrate. When the finger 2 follows up the slack as quickly as it is formed, the possibility of causing the tape to whip or vibrate either from the sudden striking of the tape by the finger or the striking of the tape by the type

of the ticker is practically avoided. In other words, the finger 2 by this means holds the tape throughout the operation of the ticker in intimate engagement with the guide 8 so that no separate vibration dissipating device need be formed at this portion of the light aperture 3.

The change of speed transmitted to the tape pulling roller 6 will correspond substantially with the change of speed of discharge of the tape. In an active market, the ticker will of course be operated at high speed and rarely come to rest. If the tape pulling device were operated always at a faster speed than the speed of discharge of the tape, as has been the custom heretofore, there is of course the danger of exercising an undue amount of pull on the tape, at any rate a greater pull than is necessary to pull the tape across the light aperture.

With the present arrangement, when the ticker is operating at high speed, the tendency to form a greater loop occurs as a result of which however the friction wheel 33 is moved nearer the periphery of the friction disc 34 in turn to transmit a greater speed to the worm 25 and through it to the tape pulling roller 6.

Consequently as fast as a larger loop is formed the slack is more quickly taken up to again return the friction wheel 33 to the lower area where it receives a lower rate of speed. A very nice balancing action results in turn to produce a very even and uniform movement of the character and images on the tape.

As shown in Fig. 3, the friction wheel 33 can be easily replaced in case of wear and in turn for ordinary wear, the spring 38 will compensate adequately and if need be the collar 43 may be manipulated further to compensate for such wear.

As shown in Fig. 1, the tape T is maintained in engagement with the tape pulling roller 6 by means of the idler 62 formed at the end of the bracket 63 mounted on the pin 64 which bracket 63 and in turn idler 62 is resiliently maintained in engagement with the roller 6 by the spring 65.

The shaft 57 has formed thereon a cap 66 to which is permanently secured the disc 67 which in turn has secured thereto a hub 68. This hub 68 has a central chamber 69 to receive the spring 70 which is mounted on the spindle 71 of the key 72 and tensed between the collar 73 and the end 74 of the chamber 70 to urge the key 72 inwardly. As shown in Fig. 6 there is also provided a removable disc portion which consists essentially of the disc portion 75 having formed thereon a spring collar 76 composed of spring metal and provided with a slot 77 to permit the same to spring inwardly.

This collar 76 is intended to snugly grip the hub 68 when in place as shown in Fig. 2 and to prevent the collar 76 from turning when mounted on the hub 68 there is provided the recess 78 which engages the pin 79, see Fig. 5 which extends from the hub portion 68. The disc portion 75 further has a slot 80 in length and width corresponding to the key finger piece 81 of the key 72 so that the disc portion 75 may freely slide over the key 72 when securing the collar 76 on the hub 68 after which the key 72 is merely drawn outwardly sufficiently to clear the disc portion 75 and then turned substantially at right angles to the slot 80 as shown in Fig. 7 to engage the outer face of the disc 75 and thereby maintain the disc 75 in place against accidental displacement.

For threading a strip of tape on the collar 76, there is formed a pin 82 extending from the face of the disc 75 adjacent to the collar 76, see Figs. 75

6 and 7. The end of the tape is merely slipped under the pin 82 and then folded backwardly in opposition to the direction of rotation.

By means of this reel a strip of tape can be quickly threaded on the removable portion before the same is mounted on the fixed portion 67 and in turn by means of the key 72 the removable portion quickly removed when the reel has been filled in turn to remove the tape from such reel.

10 It is obvious that various changes and modification may be made to the details of construction without departing from the general spirit of the invention as set forth in the appended claims.

I claim:

15 1. In a stock quotation projection machine, the combination with a projection field, of a tape pulling device for drawing the tape across said projection field as it is fed thereto, a driving disc continuously operating at a uniform rate of speed, 10 a speed changing device having a friction wheel in frictional engagement with said driving disc and operatively connected to said tape pulling device, a control lever having an elongated arm and a short arm, the end of the elongated arm resting on the tape in advance of the projection field to exercise a tension on the tape to cooperate with the pulling device to maintain the same smooth at the projection field and to respond to deflections in the tape, the end of the short arm 20 of said control lever being operatively connected to support said friction wheel to change the position of said friction wheel relative to the center of said driving disc according to the deflection in said tape, and a spring cooperating with said lever 25 to take up the slack in said tape as quickly as formed.

2. In a stock quotation projection machine, the combination with a projection field, of a tape pulling device for pulling the tape through said projection field, a driving disc continuously operating at a uniform rate of speed, a rotatable member operatively connected to said tape pulling device, a vertical spindle slidable in said rotatable member and being fixed to rotate therewith, a friction wheel fixed on said spindle in frictional engagement with said driving disc, and a lever resting on the tape in advance of the projection field to exercise a tension on the tape to cooperate with the pulling device to maintain the same smooth at the projection field and responsive to deflections in the tape, said lever being operatively connected to support said spindle to change the position of said friction wheel relative to the center of said driving disc according to the deflection in the tape.

3. In a stock quotation projection machine, the combination with a projection field, of a tape pulling device pulling the tape across the projection field, a driving disc continuously operating at a uniform rate of speed, a rotatable member operatively connected to said tape pulling device, a vertical spindle slidable in, and fixed to rotate with, said rotatable member, a friction wheel mounted on said spindle, means for resiliently pressing said driving disc into frictional engagement with said friction wheel, and a control lever having one arm in engagement with the tape in advance of the projection field to exercise a tension on the tape to cooperate with the pulling device to maintain the same smooth at the projection field and movable in response to deflections of the tape, said control lever having its other arm operatively connected to support said spindle to change the position of said

friction wheel relative to the center of said driving disc according to the deflection in the tape.

4. In a stock quotation projection machine, the combination with a projection field, of a tape pulling roller for pulling the tape through said projection field, a driving disc continuously operating at a uniform rate of speed, a worm operatively connected to said tape pulling roller, a vertical spindle slidable in, and fixed to rotate with, said worm, a friction wheel mounted on said spindle and in frictional engagement with said driving disc, and a control lever having one end thereof resting on the tape in advance of the projection field to exercise a tension on the same to cooperate with the pulling roller to maintain the tape smooth at the projection field and responsive to deflections in the tape, said lever having its other end operatively connected to support said spindle, said control lever being fulcrumed between its ends and operative to change the position of said friction wheel relative to the center of said driving disc according to the deflection in the tape.

5. In a stock quotation projection machine, the combination with a projection field, of a tape pulling roller at the discharge end of the projection field to pull the tape therethrough, a driving disc continuously operating at a uniform rate of speed, a friction wheel in frictional engagement with said driving disc and operatively connected to said pulling roller, an elongated control lever having one end resting on and in engagement with the tape in advance of the projection field to exercise a tension on the same to cooperate with the pulling roller to maintain the tape smooth at the projection field and responsive to deflections in the tape, said lever having its other end operatively connected to support said friction wheel, said lever being fulcrumed between its ends and operative to change the position of said friction wheel relative to the center of said driving disc according to the deflection in the tape, and a spring cooperating with said lever to follow up the slack in said tape as quickly as formed.

6. A variable speed device for controlling the feed of tape having a driving disc, a friction wheel in frictional engagement with said disc, a vertical spindle on which said friction wheel is fixed, a tape feeding device operatively connected to said friction wheel, and a lever responsive to the tension in the tape operatively connected to support said spindle to change the position thereof relative to the center of said driving disc according to the tension in the tape.

7. A variable speed device for controlling the feed of tape having a driving disc, a friction wheel, means for pressing said driving disc into frictional engagement with said friction wheel, a vertical spindle on which said friction wheel is fixed, a tape feeding device operatively connected to said friction wheel, and a lever responsive to the tension in the tape operatively connected to support said spindle to change the position thereof relative to the center of said driving disc according to the tension in the tape.

8. In a stock quotation projection machine, the combination with a tape pulling device, of a driving mechanism having a driving disc continuously operating at a uniform rate of speed, a speed changing device having a friction wheel in frictional engagement with said driving disc, a vertical spindle on which said friction wheel is fixed and operatively connected to said tape pulling device, and a lever responsive to deflections

in the tape to be drawn by said pulling device, one arm of said lever operatively connected to support said spindle and the other arm resting on the tape to be drawn for changing the position 5 of said friction wheel relative to the center of said driving disc according to the speed to be attained.

9. In a stock quotation projection machine, the combination with a tape pulling device, of a 10 driving disc continuously operating at a uniform rate of speed, a speed changing device having a friction wheel in frictional engagement with said driving disc, a vertical spindle on which said friction wheel is fixed and operatively connected to 15 said tape pulling device, a lever responsive to deflections in the tape to be drawn by said pulling device, one arm of said lever being operatively connected to support said spindle and the other arm resting on the tape to be drawn for changing 20 the position of said friction wheel relative to the center of said driving disc according to the speed to be attained, and a spring co-operating with said lever to follow up the deflection in the tape as quickly as formed.

10. In a stock quotation projection machine, the combination with a tape pulling device, of a 25 driving disc continuously operating at a uniform rate of speed, a speed changing device having a friction wheel in frictional engagement with said driving disc, a vertical spindle on which said friction wheel is fixed and operatively connected to said tape pulling device, and a control 30 lever responsive to the tension in the tape and

operatively connected to support said spindle to control the position of said friction wheel relative to the center of said driving disc according to the speed to be attained.

11. The combination with a tape pulling device, of a driving mechanism having a driving disc continuously operating at a uniform rate of speed, a friction wheel in frictional engagement with said driving disc, a slidably mounted spindle on which said friction wheel is fixed and 10 operatively connected to said tape pulling device, and a lever responsive to deflections in the tape to be drawn by said pulling device, one arm of said lever operatively connected to support said spindle and the other arm resting on the tape 15 to be drawn for changing the position of said friction wheel relative to the center of said driving disc.

12. The combination with a device for pulling tape across a support having a light aperture, of 20 a friction drive including a driving member and a driven member, and a pivotally mounted lever, one arm of said lever resting on the tape at the anterior end of the light aperture and responsive to deflections in the tape to be drawn by said 25 pulling device and the other arm of said lever operatively connected to support said driven member and effective to relieve the pressure on the tape by said first arm but fixed to move with said first arm to change the position of said 30 driven member relative to said driving member.

FRANK E. ANDERSON.
